UNITED STATES PATENT OFFICE.

JOHN R. MOFFITT, OF CHINESE CAMP, CALIFORNIA.

HEEL-STIFFENER MACHINE.

SPECIFICATION forming part of Letters Patent No. 327,710, dated October 6, 1885.

Application filed April 11, 1885. Serial No. 161,880. (No model.)

To all whom it may concern:

Be it known that I, JOHN R. MOFFITT, a citizen of the United States, residing at Chinese Camp, in the county of Tuolumne and State 5 of California, have made and invented certain new and useful Improvements in Machines for Shaping Heel-Stiffeners for Boots and Shoes; and I do hereby declare that the following is a full, clear, and exact description of my said 10 invention, reference being had to the accompanying drawings.

My invention relates to improvements made in machines for shaping and finishing heel-stiffeners for boots and shoes; and my improvements in respect thereof consist in certain improved construction and combination of parts, producing a pressing and shaping machine of improved character.

This machine is produced by forming and 20 combining novel dies or formers constructed in accordance with certain improvements heretofore made the subject of an application for Letters Patent by me under Serial No. 161,878, and suitable mechanism for moving 25 and operating the dies. A hollow expandible die or "former," of suitable elastic or yielding material, formed with an exterior cavity, and a hard-metal solid or unyielding die or former adapted to be in said cavity composed 30 the forming and pressing surfaces, between which the blank or piece of material is placed to be pressed and brought into shape. The hollow expandible one of such pair of dies is filled with a suitable fluid or liquid, and a 35 means for applying pressure thereto is combined with the die in such manner as to produce expansion of the wall or active surface of the die and to force it out at all points against the other die when the two dies are 40 brought together. Mechanism for applying this pressure to produce expansion of the wall of the hollow die and for bringing the dies together and for separating them is constructed 45 as follows, the said drawings being referred to by figures and letters.

Figure 1 is a front elevation of my improved machine, and Fig. 2 is a side elevation taken from the right-hand side of Fig. 1. Fig. 3 is a vertical section through the expandible die 50 and the liquid-chamber as it is in position upon the solid die, a heel-stiffener in place ss

of shaping being shown between the two shaping-surfaces. Fig. 4 is a plan of the solid die and the supporting-table. Fig. 5 is an outside view of the expandible die. Fig. 6 is a cross-section through the rigid-surface die. Figs. 7 and 8 represent a heel-stiffener both before and after the finishing operation.

The expandible die A is constructed of some hard elastic material impervious to air, gas, 60 and water, and capable of a certain amount of expansion, or the property of being stretched and of returning again to its normal condition of form when the stretching force is removed, and having also a certain practical strength to 65 withstand required pressure. Rubber is the material I employ as best suited to the purpose.

The body of the die is hollow, and the hollow space a^x is filled with a liquid or fluid by 70 having the space connected with or made a continuation of a cylinder, D, fitted with a piston, E, the movement of which in one direction transmits pressure against the walls of the hollow die in all directions by virtue of 75 the confined body of fluid or liquid being compressed beneath it.

The other or fixed die, A x , is a metal block set on a stationary bed, B, in position beneath the movable die.

The movable die is set in a reciprocating head, P, composed of two heads, p p^x , bolted together to form a single slide. On the lower one, p^x , of these parts is a hollow cylindrical chamber, d^x , open at both ends, into which the hollow die is fitted, and on the lower face of the other part, p , of the head a circular rim or flange is formed to fit around the edge of the cylinder. The die a has a turned-out flange, a^x , which is clamped between these parts when 90 the heads p p^x are bolted together. The upper plate, p , has the liquid-cylinder D, open at the bottom to communicate with the hollow space of the die, but closed at the top by a head, E x , with a stuffing-box, through which the rod E x of the piston E is fitted to work. The piston is set loosely in the cylinder to permit the passage of liquid above it on the downstroke, so that a portion of the liquid from below may escape around the side of the piston into the space above to cushion the upstroke.

The piston-rod E x is attached at the upper

end to a cross-head, H, moving vertically on upright guides I and connected to cranks by connecting-rods J J, and then the piston-rod is operated to give pressure to the confined expanding medium in the cylinder and die, and to move the sliding head as well.

Large spur-wheels K K are mounted on opposite sides of the frame X X on bearings k, and the rods J are connected to wrist-pins k².

10 A common driving-shaft, L, is geared into these wheels by pinions L² to apply power to both cranks equally. M is a pulley on the shaft L to give motion from a belt.

15 The cylinder D is supplied with liquid by a pipe, N, fitted with a suitable valve, which may be applied to open inward, so as to admit liquid from the supply-pipe into the chamber, but to prevent its escape. This will insure a required amount of liquid in the 20 space within cylinder and die at all times.

The expanding medium can be a fluid, as air or gas, or a liquid, as water, alcohol, glycerine, or any other liquid that will not act injuriously on the rubber.

25 The unyielding die A^x is fixed in the bed, and, in cases where heat is to be employed in connection with pressure to shape and finish any objects, the die is formed of a metal block with a heating-chamber, b², having a pipe, b³, to admit steam or hot air.

30 A device for throwing out portions of the acting surface of the expandable die is employed in those forms where overhanging or undercut parts may be used in the die, the construction and action of which device is shown in Figs. 1, 2, and 3. It consists of two sliding wedge-shaped blocks, R R, movable through slots b b in the bed, and set in such position with respect to the movable die A and its surrounding case or cylinder that on the downward movement of the die over the fixed die A^x, and as the two dies come together, the tapering edges of the blocks enter between the cylinder and the contained die A^x in such manner as to 35 press the adjacent walls of the die inward. The effect of this action is to throw the acting surfaces of the die A inward or toward the fixed die, and by a proper form and application of these wedges parts of the expandable die can be o pressed into depressions or under overhanging parts of the fixed die to bring a close fit and required pressure of the two acting surfaces. Fig. 3 illustrates the position of parts when these wedges are acting, and Fig. 1 5 shows the condition before they enter between

the movable die and the cylinder. These wedges are operated from a cam-shaft, S, that is geared into the driving-shaft, as shown in Figs. 1 and 2.

60 The blocks R R are connected by the plate R^x, from which depend two short rods or posts, R², carrying at the lower end a cross-bar, R³.

65 A cam, S^x, in the shaft below is of suitable form to produce alternate rising and falling movement of this movable frame and thereby project the blocks R through the bed at the proper times and draw them back as required.

70 I claim—

1. The combination of a suitable frame, a metallic or hard surface die, a hollow elastic or expandable surface die having its cavity filled with liquid, a liquid-cylinder having connection with this cavity of the die and fitted with a piston or plunger as a means for expanding the die, and mechanism for bringing one die against the other and for operating the liquid-pressure by which the elastic-surface die is expanded, substantially as hereinbefore described. 75

2. The combination of the stationary metallic or hard surface die, the hollow elastic or expandable surface die confined within a movable head and surrounded by an unyielding case or shell, and the movable wedges adapted to enter between this case or shell and the sides of the elastic die at the time of operation as the two dies are brought together, substantially as hereinbefore described, for the 80 purpose set forth. 85

3. In a machine for the purposes described, the combination of the movable head containing the hollow elastic die, the liquid-cylinder communicating with the hollow or cavity of the said die and fitted with a piston or plunger operated as described, and the stationary metallic or hard surface die mounted on a bed in relation to the movable die, substantially as set forth. 95

4. The combination, with the hollow elastic die or former within the surrounding case or shell, of the wedges, and the rigid die, said wedges being adapted to press the elastic die into any unevennesses, curves, or angles of the rigid die, substantially as set forth. 100

JOHN R. MOFFITT. [L. S.]
